ONION GRADING ROLLERS

Richard D. Sheppard, Bridgeton, N. J.

Application April 22, 1944, Serial No. 532,329

1 Claim. (Cl. 15—3.11)

1

This invention is a device for cleaning and size grading objects such as onions, potatoes, beets, flower bulbs and like objects which can be advantageously cleaned and size graded to enhance their marketability.

Objects and advantages of the invention will be set forth in part hereinafter and in part will be obvious herefrom, or may be learned by practice with the invention, the same being realized and attained by means of the instrumentalities and combinations pointed out in the appended claim.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Objects of this invention are to provide a new and useful device for cleaning, and grading objects of the nature aforesaid to the end that the cleaning, grading and sacking of such objects can be performed in a more rapid and commercially practical manner with great savings in time, labor, and equipment and in operating cost.

Of the drawings:

Fig. 1 is a view in top plan of a presently preferred embodiment of this invention with parts omitted for better understanding;

Fig. 3 is an enlarged fragmentary view in plan of the embodiment of Fig. 1;

Fig. 4 is a view in section of the embodiment of Fig. 1 taken along the line 4—4 of Fig. 3; and

Fig. 5 is an enlarged isometric view of the delivery end of one of the rollers of the embodiment of Fig. 1.

This invention comprises a set of elongated cleaning and grading members mounted for rotation on their lengthwise axis, to which objects, such for example, as onions, to be cleaned, graded and sacked, may be fed at one end and from the other end of which the objects are delivered in a clean state and in separate streams made up of the different sizes of onions, respectively. For example, the onions of a size equal to or larger than one and one-half inches, that is, onions of the so-called U. S. No. 1 grade, may be delivered in one stream; and, the smaller onions, that is, onions of the so-called U. S. No. 2 grade, or U. S. seconds, delivered in a separate stream.

Additionally, the invention comprises means for collecting the onions of one of the streams comprised, for example, of the smaller onions

2

and for delivering these onions to one or another or all of a plurality of receiving stations.

The invention further comprises the combination of the set of power driven cleaning and grading members and the collecting and delivering means for one of said streams, with a self-propelled vehicle upon which the foregoing are mounted for convenient transportation and of which the engine may serve as a prime mover for the set of cleaning and grading members.

It will be understood that the foregoing general description and the following detailed description as well are exemplary and explanatory but are not restrictive of the invention.

15 To the accomplishment of the foregoing ends and objects and in accordance with this invention there is provided an elongated frame structure 10, which may be of wood, metal or any other suitable material, and in which a set of parallelly arranged elongated cleaning and grading members 11 are mounted for rotation on their lengthwise axes and mechanically coupled for simultaneous rotation in the same direction at the same speed.

The frame structure 10, as embodied, is open 25 at the top and bottom, is of generally rectangular shape and is supported by suitable structural means so as to assume an upwardly inclined position from front to rear, that is, from left to right, as viewed in Fig. 4, and from its feed end 30 to its delivery end, that is from right to left as viewed in Fig. 2, in its normal operative position. As here preferably embodied, it comprises front and rear wooden frame members 12 rigidly connected in spaced, parallel vertical relation to each 35 other by parallel vertical end frame members or headboards 13 at the delivery end and the feed end, respectively of the frame structure.

Each of the rotary cleaning and grading members 11 extends substantially the full length of 40 the frame structure 10 between the frame members 13, with the rotational axes of the members in a common plane inclined upwardly from front to rear, as is best seen in Fig. 4, and from the feed end to the delivery end, as is shown in Fig. 2.

45 A minimum of two of the rotary members 11 may be used but a larger number is preferred to provide a capacity sufficient to process the onions at commercially practical rates. Accordingly, and as here preferably embodied, three pairs of 50 the rotary cleaning and grading members 11 are provided, the members being of identical construction so that a description of one is equally applicable to any and all of the others.

Each cleaning and grading member 11 as embodied is in the nature of a screw having a rela-

tively large diameter portion extending throughout a major portion of its length forming a cleaning section, and having a smaller diameter portion over the rest of its length forming a sorting or grading section. As here preferably embodied each member 11 comprises a wooden body portion 14 of cylindrical contour having a cleaning section 16 of one diameter and a sorting section 17 of lesser diameter. A rope 18 is wound in helical fashion about the body portion 14 of the member from end to end over the sections 16 and 17, each turn of the rope being fastened to the body portion 14 by staples 19 and being equally spaced from the next by a determined equal amount over the length of the cleaning section 16 and by a lesser equal amount over the length of the sorting section 17. A shoe 18' preferably of metal covers the delivery end of each rope to prevent fraying of the rope end and is anchored to the body portion 14 as by means of screws 18''. Each shoe 18' preferably forms a continuation of the rope helix over the sorting section 17 of the members 11 and has an inclined top surface from adjacent the rope end to the surface of the body portion 14. Axles 20 and 21 project from the opposite ends of the body portion 14 for rotatably mounting the members 11 between the frame members 13. The axles 20 are journaled in suitable bearing members 22 carried by the left-hand frame member 13 and the axles 21 are journaled in the right-hand frame member 13.

The bearing members 22, one for each of the axles 20, are bolted or otherwise suitably anchored to the left-hand frame member 13 along its upper edge which slants upwardly from front to rear at an angle corresponding to the desired common plane of the axes of the members 11. Similarly, the right-hand frame member 13 is apertured to receive the axles 21 in accordance with the same purpose. Obviously, anti-friction bearing members (not shown) may be provided in the headboard 13 for the axles 21, as required.

The spacing of the rotary members 11 on their axes is of sufficient magnitude that dirt and skin removed from the onions by the rubbing, tumbling and abrasive action of the ropes 18 may fall between the body portions 14 over the cleaning section 16 to the surface below and yet is not of such magnitude that the onions of the smallest desired size may fall therebetween throughout the length of the cleaning section.

A baffle roller 23 is revolvably mounted between the frame members 13 in a position generally above and to the rear of the rearmost rotary member 11 in axially parallel relation thereto. The baffle roller 23 is of cylindrical or substantially cylindrical contour and of uniform diameter and is provided with axles 24 and 25 at its opposite ends. The axle 24 journaled in a bearing member 26 carried by the left-hand frame member 13 and the axle 25 is journaled in the right-hand frame member 13 through which it passes and is connected to driving mechanism by which it is rotated, as will be described more fully hereinafter.

A baffle board 27 is carried by the rear wall 12 of the frame structure 10 in a position generally above and to the rear of the baffle roller 23 and in parallel relation thereto. The baffle board 27 slants upwardly from front to rear from a position closely adjacent to the baffle roller 23 to the rear wall member 13 and in conjunction with the baffle roller 23 serves to return to the cleaning and grading members 11, those onions which may be thrown upwardly thereagainst by the members 11.

The rotary members 11 and the roller 23 are suitably interconnected at their feed end so as to be driven simultaneously at the same speed in a clockwise direction, looking from the feed end to the delivery end of the device. The rope 18 on each body portion 14 is wound in the opposite direction, however, so as to effect a movement of the onions from the feed end to the delivery end of the members 11. The front rotary member 11 carries on its axle 20 a sprocket 28, Fig. 8, having a single row of teeth and the axle 25 of the baffle roller 23 carries a sprocket 29 of the same diameter having the same number of teeth. Each of the other members 11 carries on its axle 21 a sprocket 30 of the same diameter, but with a double row of teeth, the several sprockets being suitably interconnected by means of heavy duty roller chains 31 so as to be driven together in the same direction at the same speed when power is applied to one.

Because of the close spacing of the members 11 and the thickness of the ropes 18, the members 11 must be timed with relation to each other so that each turn of the rope on one will lie just beyond the turn on the preceding member. In connecting the members 11 by means of the chains 31, they are accordingly angularly adjusted with relation to each other so as to avoid any interference between adjacent turns of the ropes.

A housing wall 32 parallels the right-hand headboard 13. The axle 21 of one of the center pairs of the rollers 11 is extended across the sprocket housing thus formed and is journaled in the wall 32. A sprocket 33 of larger diameter than the sprockets 28, 29 and 30 is secured to this extended axle. A roller chain 34 connects the sprocket 33 with a driving sprocket 35 of smaller diameter secured to a pulley shaft 36 also carrying a pulley 37.

A tensioning shaft 38 parallels the axles 21 and is journaled at its ends in the housing wall 32 and in the right-hand headboard 13 and carries therebetween an eccentric journal member 39 fixed to the shaft. A pair of pulley arms 40 extend rearwardly therefrom in spaced parallel relation to each other. The arms 40 are journaled on the journal member 39 at their front end and support the shaft 36 at their opposite end with the sprocket 35 situated between the arms. The shaft 38 preferably extends through the housing wall 32 for convenience in turning the shaft to effect a back or forth movement of the arms 40 and a consequent tightening or loosening of the chain 34 through the cam action of the eccentric journal member 39.

The driven pulley 37 is preferably readily removably secured to the pulley shaft 36 so that pulleys of different diameters may be utilized for driving the members 11 at selected differing speeds. Power is supplied to the pulley 37 by means of a belt 41 connecting the pulley 37 to a driving pulley 42 of a suitable prime mover such, for example, as the engine 43 of an automobile upon whose chassis 44 the frame structure 10 is preferably mounted in suitable fashion.

Means are provided for tensioning the belt 41 so as to control the flow of power from the prime mover 43 to the members 11 at will. As here preferably embodied, a link 45 is hingedly connected at its lower end to the arms 40 intermediate their ends and also at its upper end to a lever 46 fulcrumed on a shaft 47 extending between the headboard 13 and the housing wall 32. Any suitable means may be provided for locking the lever 46 in the desired position.

Means are provided beneath the sorting section 17 of the members 11 for collecting the onions which drop between the members 11 over this section and for delivering these onions to one or another of a plurality of receiving stations. The collecting and delivering means as embodied is in the nature of a bin situated immediately beneath the sorting section 17 of the members 11, the bin having valved discharge openings at the front and an inclined floor of openwork construction along which the onions travel to the openings and through which floor onion cleanings may drop to the ground below. As here preferably embodied, front and rear wall members 50 and 51, respectively, are held in spaced parallel relation to each other by parallel left and right side walls 52 and 53 respectively to form a rectangular enclosure open at its top and bottom and extending from front to rear beneath the sorting sections 17. Vertical posts 55 at the sides of the enclosure are secured to the side walls 52 and 53 and to the front and rear wall members 12 for supporting the enclosure from the frame structure 10. A partition member 56 extends between the wall members 50 and 51 parallel to the side walls 52 and 53 and divides the enclosure into right and left hand compartments as seen in Fig. 3. Baffle members 57 at the front of the left-hand and right-hand compartments, respectively, are provided to control the discharge of onions from each compartment, as will be described more fully hereinafter.

Grating members 59 extend in spaced parallel relation to each other between the partition member 56 and the side walls 52 and 53 from adjacent the front wall 50 substantially the length of each compartment. These members are supported on edge at their ends in slots in parallel front and rear footings 60 and 61, respectively positioned at different levels so as to form an open-work floor or grating substantially paralleling the plane of the roller axes. The opening formed between the grating members 59 and the front wall member 50 in each compartment is normally closed by the baffle member 57 which may be withdrawn or tilted to permit the flow of onions through the opening into a basket which may be carried beneath the opening on a shelf 62 vertically adjustably supported from the side wall members 52 and 53.

The unit as a whole is preferably mounted on the auto chassis 44 to which it may be secured in any suitable and convenient fashion so as to position the frame structure at the desired angle and enable its transport with convenience. For convenience in depositing the onions on the members 11 at the feed end of the members, an inclined platform 109 may be secured to the frame structure 10 at the feed end of the rollers.

In operation the onions are dumped onto the rapidly rotating cleaning and grading members 11 at the feed end of the machine and are transported by the rope 18 to the delivery end. By reason of the close spacing of the body portions 14 of the members 11 throughout the cleaning sections 16 only the skin and dirt from the onions will fall therebetween as the onions are transported along the cleaning sections 16. The greater spacing between the body portions 14 over the sorting section 17 and the lesser pitch of the rope 18 enables the smaller No. 2 onions to drop between the rollers over this section onto the grating formed by the slats 59 positioned beneath the sorting section. These smaller onions may be released from either or both of the compartments into which this collecting station is divided by the partition wall 56, by retracting either one or the

other or both of the closure members 57 so as to allow the onions to pass through the opening between the front ends of the slat members 59 and the front wall member 50, into baskets which may be positioned therebelow on the platform structure 62.

The larger onions, of say U. S. No. 1 grade, are delivered in a steady stream from the delivery end of the sorting section 17.

10 By way of example in a commercial size apparatus for cleaning and grading onions in accordance with this invention, the members 11 may be 9 feet 5 1/2 inches long and of 3 1/2 inches diameter from the feed end to the grading section 17 15 where the diameter may be reduced to 2 3/4 inches throughout the 2 foot length of this section. The members 11 are preferably spaced 4 1/4 inches on their axes so as to provide a 3/4 inch space between the rollers over the cleaning section 16 through 20 which the dirt and dead skin falls.

The rope 18 around each body portion 14 may, under these circumstances, be 5/8 inch in diameter and is wound around the portion 14 from end to end in such fashion that the turns are uniformly spaced 3 1/2 inches from each other over the cleaning section 16 and 1 1/2 inches from each other over the sorting section 17.

The roller sprockets 28, 29, 30 and the driving pulley 37 are selected so as to drive all the rollers 30 in the same direction, clockwise, as viewed from the feeding end of the rollers, and in the same directions at the desired speed. A speed of approximately 55 R. P. M. has been found to be satisfactory for a unit of these dimensions although 35 a higher or lower speed may obviously be employed. At this speed, the rope friction spins the onions over and over to rub off the dead skin and dirt. It also distributes the onions all over the rollers, and at the same time conveys them to the 40 delivery end of the rollers and thus to the chute.

The roller frame structure 10 is suitably dimensioned to provide the necessary inclination of the rollers 11 from end to end and from front to rear. Assuming the roller frame structure 10 to be 10 1/2 45 feet outside dimension between the frame members 13 and 2 feet 10 inches outside dimension between the front and rear frame members 12, then the frame structure may be provided with a 10 inch rise from front to rear and a 10 inch rise 50 from the feed end to the delivery end to establish the desired inclination of the plane of axes of the members 11.

Illustrative of the advantages obtainable 55 through the use of this invention, a commercial unit of the foregoing dimensions is capable with a crew of seven men of cleaning, grading and sacking an average of 330 fifty-one pound sacks of U. S. No. 1 grade onions an hour, thus replacing the man hours of fifty men. Such a unit has cleaned, graded and sacked 33,000 such sacks in 60 100 working hours, with a crew of seven men.

The invention in its broader aspects is not limited to the specific mechanisms shown and described but departures may be made therefrom 65 within the scope of the accompanying claim without departing from the principles of the invention and without sacrificing its chief advantages.

What I claim is:

70 Onion cleaning and grading apparatus comprising in combination: a set of elongated cleaning and grading rollers for receiving onions to be cleaned, graded and sacked at one end and for delivering said onions in a clean state and in separate streams according to size at the other end, said rollers being supported for rotation on their 75

respective lengthwise axes, the respective rotational axes of said rollers paralleling each other in a common plane which plane is inclined upwardly both from the receiving end to the delivery end of said set and transversely of the rotational axes of said rollers, each said roller comprising a body member of cylindrical contour having a rope wound spirally thereon from end to end for rubbing, tumbling and abrading the onions, each body member being spaced from the adjacent body member throughout the major portion of its length by substantially only the diameter of said rope thereby to form a cleaning section, each said body member additionally being of reduced diameter over the rest of its length thereby to form a sorting or grading section and the ropes on said body members being wound in the same direction with each rope having each turn equally spaced from the next by a determined amount over the entire length of the cleaning section and by a lesser equal amount over the length of the grading section; and, means for mechanically coupling

said rollers for simultaneous rotation in the same direction at the same speed.

RICHARD D. SHEPPARD.
